UNITED STATES PATENT OFFICE.

ROBERT W. DAVIS, OF OZONE PARK, NEW YORK.

HAND AND FOOT POWER DEVICE.

Application filed April 18, 1922. Serial No. 555,033.

This invention relates to power devices and particularly to the type wherein the use of the hands will aid in doing the work as well as the feet.

Another object is to provide a device which will have few parts, be capable of manufacture at low cost and will make use of all of the operator's energy.

While I am aware that various devices of this kind have been produced in the past, I believe that the same have lacked a feature, that is highly important. So the success of such devices that is the combined use of the arms and legs for operation in such a manner as to obtain the maximum amount of power.

Another equally important object is the provision of a specially shaped operating shaft through which the combined power produced by the operators legs and arms will be delivered.

Other objects and advantages in the structure will be brought out in the following specification and drawing in the latter of which:

Fig. 1 is a front elevation of my device showing the relation of the operating elements.

Fig. 2 is a side elevation of my device.

Fig. 3 is an enlarged section taken on line 3-3 of Fig. 1.

Referring to the drawings in detail 10 designates in its entirety a power device comprising a center bar or frame 11 made of wood or any suitable metal. For the purpose of illustrating my invention I am showing it as a polished wooden bar, the upper portion of which may be square as at 12, to accommodate the guide plate 13 attached thereto, the purpose of which will be herein- 40 after explained.

The lower end of the bar 11, has attached thereto a bearing 14, in which the journal portion 15 of the crank shaft 16 revolves. This bearing 14, in the event that a metallic bar 11 be used, may comprise a bearing member having a threaded bore, into which the lower end of the bar may be screwed. It is to be understood that bar member 11 may be made of aluminum tubing or any light metallic construction, in which case the bearing member 14 would be made integral therewith or could be soldered thereon.

For the purpose of illustration the side having the breast straps shown in Fig. 2 attached thereto, will be called the back of the device.

The bearing 14 forms the upper terminus of a lightly constructed bracket 17 which is integral therewith. Spaced guide collars 18 are formed on said bracket and support the power shaft 19, to the lower end of which is suitably secured a gear or pulley through which the power may be transmitted to do useful work.

To the upper end of shaft 19 and resting on top of the upper guide collar 18 is suitably secured a bevel pinion 21 which is operated through the medium of a bevel gear 22 pinned to the journal portion 15 of the crank shaft 16 and adapted to revolve therewith. It can thus be seen upon inspection of Figs. 1 and 2 that the bevel pinion 21 and gear 22 are held in fixed spaced relation.

The crank shaft 16 is bent to a particular configuration that is, all the points on said crank shaft to which force is applied by either arms or legs, are at the same distance from the turning point and therefore travel in the same diameter of circle. These positions are attained by bending the crank shaft 16 on the left side of the device (as indicated by the L in Figs. 1 and 2) upwardly and rearwardly as at 23 and to form a journal 24 which is engaged by the left arm-operated member 25. The crank shaft is then bent downwardly and forwardly as at 26 and to form a pedal supporting portion 27. The crank-shaft on the right side (as indicated by R in Figs. 1 and 2) is bent in the opposite directions, that is, it extends down and forward to form the journal 28 for the right arm-operated member 29, and up and to the rear to form a pedal supporting portion 30. Suitable straps 31 may be used to keep the operators feet upon the 95 pedals.

Suitably attached to the upper ends of the arm operated members 25 and 29 are hand grips 32, which are held adjacent to the guide plates 13 on the frame 11. The guide plates (Fig. 3) are attached, as by screws, to the upper portion of the frame 11 so as to form slots 33 therebetween for the reception of pins 34 having enlarged portions 35 formed thereon. These portions 35 lie between the guide plates and the frame and are adapted to partake of the reciprocations of the handles 32.

To the upper end of the frame may be attached a leather, canvas or rubber adjustable body encompassing member 36.

A seat 40 may be provided which is se-

cured to and has suitable adjustable relation with the frame 11. The arm operated members 25 and 29 may also be provided with suitable adjusting means whereby their length may be decreased or increased as necessary.

In operation the device may be fastened to the body of the wearer, and through the medium of adjustment of seat and arm operated member can be made to fit any person.

The right arm-operating member 29 will be at its lowermost position when the left pedal has passed the vertical center line of the device, and until this time, it can be seen upon inspection of Fig. 2, the left arm-operating member 25 will assist the horizontal or crosswise movement of the right pedal. With this arrangement there is imparted to the shaft 19 a continuous rotary movement which will be nearly equal at all times. In the present devices when the feet are up and down respectively, there is a slowing up of the power shaft 19 due to passing the "dead center" or the point at which the feet of the operator act in a downward direction.

When the right hand crank 28 goes through the lower quadrant as at A, the left pedal 27 passes through the front quadrant as at B. This allows of the right arm being straight when the left foot goes down, the reason for this condition being that the greatest pull can be made with the arm straight. A much weaker pull is made with a bent arm. The same condition is true

regarding the left arm and right foot operating members.

Having described my invention, what I claim is:

1. In a combined hand and foot power device, a frame, hand gripping elements slideable on and parallel to said frame, a crank shaft, foot-pedals thereon, said hand elements being connected to said shaft, and said shaft being so shaped that one arm of the operator is extended parallel with the frame of the device when one foot is forcing a pedal down.

2. A hand and foot power device comprising a crank shaft, a frame, hand operated elements attached to and slideable on said frame and attached to said crank shaft, foot pedals on the outer ends of said shaft, and said shaft, pedals and hand operated elements being so arranged that a force greater than the weight of the operators body may be applied to said pedals.

3. A hand and foot power device comprising a frame, guide members disposed on one end of said frame, hand operated members slidably held in said guides, a crank journaled in the lower end of said frame, foot pedals on the outer ends of said crank, said hand operated members being connected to the crank intermediate said foot pedals, and the foot pedals and hand operated members being spaced ninety degrees apart at their point of connection with said crank.

ROBERT W. DAVIS.
